UNITED STATES PATENT OFFICE.

ALBERT J. BATES AND WALTER A. BATES, OF CHICAGO, ILLINOIS, ASSIGNORS TO BATES EXPANDED STEEL TRUSS CO., OF WILMINGTON, DELAWARE, A CORPORATION OF DELAWARE.

MACHINE FOR STRAIGHTENING STRUCTURAL MEMBERS.

Application filed October 24, 1917. Serial No. 198,204.

To all whom it may concern:

Be it known that we, ALBERT J. BATES and WALTER A. BATES, citizens of the United States, residing at Chicago, in the 5 county of Cook and State of Illinois, have invented certain new and useful Improvements in Machines for Straightening Structural Members, of which the following is a specification.

10 This invention relates to a machine for straightening structural members and has for its particular object the provision of means capable of selectively applying forces to a member, under the control of the operator, to rapidly straighten the member.

15 A further object of the invention is the provision of a machine for straightening structural members which is readily adaptable for use with members of varying dimensions and with which the work may be handled with a minimum of manual labor.

20 Further objects and advantages of the invention will be apparent as it is better understood by reference to the following specification when read in connection with the accompanying drawing illustrating the preferred embodiment thereof, in which—

Fig. 1 is a side elevation of the machine; Fig. 2 is a plan view thereof;

25 Fig. 3 is a side elevation of a portion of the machine on an enlarged scale;

Fig. 4 is a transverse section through the machine;

30 Fig. 5 is a plan view of a portion of the machine, and

Fig. 6 is a view in perspective illustrating the mode of operation of the machine.

35 The invention is designed, primarily, for use in connection with the expanding machine disclosed in Letters Patent No. 1,260,857, dated March 26, 1918, for the manufacture of structural metal members in accordance with the method described in Letters Patent No. 1,005,925, dated October 17,

40 1911. During the expanding operation the members sometimes become warped or otherwise bent and the machine hereinafter described has been found particularly useful in straightening such members.

45 Referring to the drawing 5 indicates a base to which legs 6 forming a frame are securely bolted. A table is supported on the legs 6, consisting of portions 7 and 8 connected by an intermediate portion 9. The

portion 7 of the table is adapted to receive 55 the structural members as they are delivered from the expanding machine and to straighten one flange of the members while the portion 8 is adapted to receive the members in reverse position to straighten the 60 other flange thereof.

In order to conveniently handle the members we provide two tracks 10 and 11 above the table and suitable traveling cranes 12 and 13 thereon having means for engaging 65 and supporting the members. Posts 14, spaced from the table, support swinging brackets 15 upon which the structural members rest after they pass the portion 7 of the table and until they are picked up by 70 crane 13 for movement in reverse direction in the machine.

Each of the portions 7 and 8 of the table are provided with two pairs of fixed abutments 16 and 17. Between the pairs of 75 abutments, each portion of the table is grooved as indicated at 18 (Fig. 6) to receive sliding blocks 19 carrying clamps 20 which hold jaws 21 firmly in position. The jaws 21 may be of different sizes and are 80 interchangeable for use with structural members of varying dimensions. Preferably the jaws 21 are recessed as indicated at 85 22 to prevent lateral movement thereof when held by clamps 20.

The sliding blocks 19 are each connected to the ends of levers 22'. The opposite ends of the levers 22' are connected by links 23. A pitman 24 connects one of the levers to an eccentric 25 on a shaft 26. A motor 27 90 is supported on the base 5 and is provided with a pinion 28 meshing with a gear 29 on a shaft 30 which is in turn provided with a pinion 31 meshing with a gear 32 secured to the shaft 26 and consequently the eccentric 25 is driven at a slow speed from the motor 27.

95 The levers 22' are pivotally mounted on ends of screws 33 loosely disposed in suitable openings in a housing 35 beneath the portion 9 of the table. Within the housing 35 pulleys 36 are mounted on each of the screws 33. The pulleys 36 bear at either side thereof against the housing, consequently, when the pulleys are rotated the screws 33 are moved 100 longitudinally to shift the pivots of the levers 22' and thereby shift the zone of travel 105 of the jaws 21 which are constantly recipro-

cated through their connection with the motor 27. To conveniently rotate the pulleys 36 we provide each with a flexible endless cable 37 extending through suitable guides 5 on the posts 14. Thus the pulleys are constantly under the control of the operator from a distance and the zone of travel of the jaws may be varied at will by grasping either side of the endless cable and exerting sufficient force thereon. The jaws travel the same distance at all times but the position of the travel of the jaws is variable and controlled by operation of the pulleys and cables so that the degree of pressure 15 exerted by the jaws upon the structural member may be varied as the condition of the work requires.

To facilitate movement of structural members on the table we provide each of 20 the portions 7 and 8 with rollers 38 arranged at either end of the table. The rollers 38 are preferably mounted on ball or roller bearings so that they are turned easily even when a considerable weight is disposed 25 thereon.

The operation of the mechanism will be readily understood from the following brief description thereof. The structural member 30 is removed from the expanding machine and delivered to rollers 38 on portion 7 of the table. The structural member will be received at a relatively high temperature, it having been heated previous to expansion. The operator then attaches the crane 12 35 glances along the member as it rests on rollers 38 and quickly determines in which direction force must be applied to straighten it. He first moves the structural member to the desired position then manipulates 40 the cable 37 to adjust the zone of movement of the jaws 21 so that one or the other of the jaws will engage the member, moving it against the abutments 16 or 17 and bending it by succession of applications of force 45 due to reciprocation of the jaws. The operator grasps the end of the structural member, his hand being of course suitably protected, moves the member slowly in the direction indicated by the arrow in Fig. 2 and 50 at the same time manipulates the cable 37 to apply force to the member at various points along its length as required. When the operation is completed the member may be disposed on brackets 15 where it is rolled 55 one half turn. It is then picked up by crane 13 and delivered to rollers 38 on portion 8 of the table where the previous operation is repeated while the member moves in the direction indicated by the arrow in Fig. 2. 60 Both sides of the member are thus straightened and it is ready for delivery.

In the operation of our machine only two men are required, one to handle the structural member on each side of the machine. 65 The straightening operation may be com-

pleted in approximately two minutes and without the necessity of reheating the member after it leaves the expanding machine. It can be readily understood therefore that we have perfected a machine which is capable of performing the desired operation in a rapid and satisfactory manner and at a minimum of labor and expense. Our machine is moreover simple in construction and is capable of continuous operation for long periods without adjustment or necessary repair.

It will be apparent that various changes may be made in the form, construction and arrangement of the parts without departing from the spirit and scope of the invention or sacrificing any of its material advantages, the form hereinbefore described being merely a preferred embodiment thereof.

We claim:

1. In a metal bending machine, a plurality of abutments defining a work-receiving guideway, work engaging jaws disposed at opposite sides of the guideway and working transversely thereof, means for maintaining the jaws spaced in a predetermined relation, means for reciprocating the jaws as a unit through a constant zone of travel; and means for adjustably shifting the zone of reciprocation of the jaws while the machine is in operation, whereby the shifting of the zone of reciprocation may be effected without stopping the machine.

2. In a metal bending machine, a plurality of abutments defining a work-receiving guideway, work engaging jaws disposed at opposite sides of the guideway and maintained in predetermined spaced relation, means for reciprocating the jaws as a unit through a constant zone of travel transversely of the guideway, and means for adjustably shifting the zone of reciprocation of the jaws while the machine is in operation, whereby the shifting of the zone of reciprocation may be effected without stopping the machine.

3. In a metal bending machine, a plurality of abutments defining a work-receiving guideway, work engaging jaws disposed at opposite sides of the guideway, means connecting the jaws as a unit and maintaining them spaced in a predetermined relation, and means for reciprocating the jaw connecting means and the jaws as a unit through a constant zone of travel transversely of the guideway and including adjusting mechanism for shifting the zone of reciprocation of the jaws while the machine is in operation, whereby the shifting of the zone of reciprocation may be effected without stopping the machine.

4. In a machine for straightening structural members, the combination of a support for a member, fixed abutments on said support to engage opposite sides of the mem-

ber, a block mounted to slide in a horizontal plane on the support beneath the member, jaws carried by the block to engage opposite sides of said member, a single means for 5 constantly reciprocating the block in a fixed length of travel, and means controlling the operation of said reciprocating means to shift the zone of travel of the jaws to cause one or the other jaw to operate on the structural member in cooperation with the opposite abutments.

5. In a machine for straightening structural members, the combination of a support for a member, fixed abutments on said support to engage opposite sides of the member, a pair of jaws mounted to slide in a horizontal plane on the support to engage opposite sides of said member, means for constantly reciprocating said jaws in a fixed length of 10 travel and including a lever, and means for shifting the fulcrum of said lever to vary the position of travel of the jaws and cause one or the other jaw to operate on the structural member in cooperation with the opposite abutments.

6. In a machine for straightening structural members, the combination of a support for a member, fixed abutments on said support to engage opposite sides of the member, a pair of jaws slidably mounted on the support to engage opposite sides of said member, means for constantly reciprocating said jaws in a fixed length of travel and including a lever, and means for shifting the fulcrum of said lever including a screw engaging the lever, a pulley for operating the screw, and a cable for operating the pulley to vary the position of travel of the jaws and cause one or the other jaw to operate 20 on the structural member in cooperation with the opposite abutments.

7. In a machine for straightening structural members, the combination of a support for a member, fixed abutments on said support to engage opposite sides of the member, a block slidably mounted on the support beneath the member, a pair of jaws on the block to engage opposite sides of the member, means for constantly reciprocating said 25 block in a fixed length of travel and including a lever connected at one end to the block and at its other end to operating means, and means for varying the position of travel of the block to cause one or the other jaw to operate 30 on the structural member in cooperation with the opposite abutments including a screw connected to said lever between its ends, a pulley for operating the screw, and a cable for operating the pulley.

8. In a metal bending machine, a plurality of abutments defining a work-receiving guideway, work engaging jaws disposed at opposite sides of the guideway, means connecting the jaws in a unit and maintaining them spaced in a predetermined relation, a

driving member, a driving connection between the driving member and the work engaging jaws for reciprocating the latter through a constant zone of travel, and means for adjusting the drive connection to shift 70 the zone of reciprocation of the jaws.

9. In a metal bending machine a plurality of abutments defining a work-receiving guideway, work engaging jaws disposed at opposite sides of the guideway, means connecting the jaws in a unit and maintaining them spaced in a predetermined relation, a driving member, a driving connection between the driving member and the work engaging jaws for reciprocating the latter, 75 said driving connection including a lever, and means for shifting the fulcrum of the lever to shift the zone of reciprocation of the jaws.

10. In a machine for straightening structural members, the combination of a pair of oppositely disposed supports to successively receive a member, fixed abutments on each support to engage opposite sides of the member, a block mounted to slide in a horizontal plane on each support, a pair of jaws on each block to engage opposite sides of the member, a single means for constantly reciprocating said blocks and including a pair of levers engaged with said blocks, and independent means located between the supports and connected with the respective levers for shifting the fulcrum of said levers to vary the position of travel of the blocks to cause one or the other jaw thereon to 80 operate on the structural member.

11. In a machine for straightening structural members, the combination of a support for a member, fixed abutments on said support to engage opposite sides of the member, a pair of jaws mounted to slide in a horizontal plane on the support to engage opposite sides of said member, means for constantly reciprocating said jaws in a fixed length of travel, and means for varying the position of travel of the jaws to cause one or the other jaw to operate on the structural member in cooperation with the opposite abutments and including a pulley, and a cable for operating the pulley and extending 95 from the machine in a position accessible to the operator traveling with the member as it travels through the machine.

12. In a metal bending machine, a plurality of abutments defining a work receiving guideway, work engaging jaws disposed at opposite sides of the guideway and working transversely thereof, means for maintaining the jaws spaced in a predetermined relation, means for reciprocating the jaws as a unit through a constant zone of travel, and means for adjustably shifting the zone of travel of the jaws while the last named means is in operation.

13. In a metal bending machine, a plural-

ity of abutments defining a work receiving guideway, work engaging jaws disposed at opposite sides of the guideway, means connecting the jaws in a unit and maintaining them spaced in a predetermined relation, a driving member, a driving connection between the driving member and the work engaging jaws for reciprocating the latter

through a constant zone of travel, and means for adjusting the drive connection to shift 10 the zone of reciprocation of the jaws while the driving member is in operation.
